INCINERATOR PROVIDED WITH DRYING
CHAMBER

Albert H. Heimbach, Allentown, Pa.

Application April 8, 1944; Serial No. 530,143

4 Claims. (Cl. 110—8)

1

This invention refers to incinerators and more particularly to an improved construction of the garbage drying chamber and furnace construction. It has among its objects to provide an arrangement that will more efficiently incinerate the material to be disposed of. Another object is to provide a system of utilizing accumulated heat in the furnace to produce a more effective action and speedier burning of the material therein. A further object is to have the furnace suitable for the burning of oil, gaseous or powdered fuel in the incinerating of the garbage or rubbish fed to the furnace.

With these and other incidental objects in view this invention consists in certain novel features of construction and combination of parts, the essential elements of which are herein-after described in an illustration of the invention outlined in the attached drawings, in which:

Figure 1 is a plan view of an incinerator illustrating an embodiment of this invention;

Figure 2 is a sectional elevation taken along line 2—2 of Figure 1;

Figure 3 is a sectional elevation taken along line 3—3 of Figure 1, and

Figure 4 is an elevational view partly in section taken along line 4—4 of Figure 2.

Similar reference characters refer to similar parts throughout the drawings:

In the construction indicated, 1 represents brickwork or masonry forming the body of the incinerator. It is set on a suitable foundation 2. The furnace drying chamber consists of a section 3 of the masonry between the front wall 4 and a bridge wall 5. The entrance 6 to this section consists of an opening in the wall 4 in which an oil burning unit 7 is installed. The flames 31 from the latter pass horizontally through the section over the pit space 8. This pit space has a draft door 9 provided close to the level of the floor 10, and is located directly under the burner unit, as shown. A transversely arcuate drying plate 11 preferably of cast iron is located across the section 3 just above the burner unit and slanting downwardly towards the bridge wall 5 at a slight horizontal angle, an opening 12 from the section over the pit space 8 serves as an outlet for the burning gases and flames from the unit 7 and is tapered by the top surface 13 of the bridge wall and that of the drying plate. There is a space 14 left in the opening above the drying plate to allow the dried rubbish to be moved through to the combustion chamber 15 of the incinerator. This chamber opens directly under the chimney 16 through which the burning gases

flow to the outside atmosphere. A grate 17 for catching the rubbish as it moves into this chamber is provided in the latter at a level below the opening 12, but close enough to be heated and yet allow a suitable accumulation of dried material to be burnt. The purpose of this is to provide for self-combustion of the material and use of its heat to reduce the consumption of the fuel from the unit 7. An auxiliary burner unit 18 is provided in the rear wall 19 of the combustion chamber for facilitating the work when special conditions require the use of same. The drying chamber is made relatively high to facilitate the evaporation of the moisture out of the garbage and rubbish injected above the inspection and draft door 20 in the front wall. Relatively small openings 21 are arranged in the breach wall near the ceiling 22 of this drying space to allow the escape of the evaporated moisture and its further heating on its way to the chimney and mixture with the combustion gases. The main dumping manhole 23 for the insertion of the rubbish is provided in the ceiling structure of this drying chamber. In the case 25 of an apartment house or hotel, the provision of receiving doors 24 is made at each floor level for the purpose of taking the rubbish therefrom. The drying plate is preferably ribbed as shown at 25, at right angles to the direction of flow of the flames from the burning unit 7. This is to increase its absorption of heat and also to divert the flames downwardly as they pass to the grate and chimney. Special bell-shaped strainers 26 of iron are inserted in the back corners at the drying chamber floor level (which is the top surface of the plate) to eliminate the accumulation of rubbish clinker at these locations.

The principles of the furnace can be appreciated from a description of its operation. The burner unit 7 is first started to heat up the drying plate 11. The garbage or rubbish is then dumped through the manhole 23 on to the plate, and the manhole cover closed. The flames and heated gases from the burner continue into the combustion chamber and rise up through the chimney. At the same time, they heat, roast and gasify any accumulations on the grate 17 and cause it to ignite and burn. The movement of these gases creates such a draft in the chimney that it draws the moisture through the openings 21, and also draws in the dried material 30 from the upper surface of the plate into the combustion chamber where it contacts the flames 31 from the burner unit and burns, while its hot ashes drop to the grate 17 below. The ashes

eventually are raked into the ash pit 27 below and taken out through the cleanout door 28. This latter door also is used for draft purposes. The strainers 26 in the corners get very hot during the process and make the rubbish in contact with it dry and powdery so it cannot cake there. If there is any considerable accumulation of water in the rubbish, it runs down to the soil pipes 29 opening under these perforated strainers and drain to the sewers below. This prevents such water from getting to the grate 17 and slowing up the combustion of the rubbish thereon. The rear wall 19 and side walls 37 and 38 of the combustion chamber is preferably restricted inwardly at 32 to induce a sweeping of the burning gases against the bridge wall, so it will heat same and draw more effectively on the vapors and gases to be removed. The use of firebrick and other conventional construction to enable the brickwork to withstand the high temperatures and abrasive actions of the combustion etc. are provided for in the customary manner without being further detailed on the basis that they are well known to those in the art. A screen 40 on the upper end of stack 16 prevents sparks from flying over the place.

The incinerator is shut down by turning off the burner 7 and allowing the combustion of the materials on the grate to complete. The walls being hot, the plate being heated and having ample power to dry the material remaining on it; the drafts within the chambers being still effective, and the walls of the furnace having much residual heat, all serve to keep the incinerator effective until the last items of the rubbish and garbage are burned up. The arcuate construction of the drying plate has been found to be free from the danger of cracking and the effects of straining the walls of the incinerator excessively during the variations in temperature from normal to combustion conditions, and more evenly distribute on the grate the materials to be burned.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention what is claimed is:

1. An incinerator comprising wall means defining a chamber, a partition extending across said chamber and dividing same into a fire box and a drying compartment, a chimney formed in the roof of said fire box for carrying off the fumes and also acting as a passage for feeding the material to be burned from a higher level directly into the fire box, said partition having an aperture therein providing communication between said fire box and said drying chamber, an inclined drying plate mounted between the front and partition walls with one end projecting through the aperture into the fire box at a point intermediate the top and bottom of said aperture and having the other end extending into said drying compartment, a fire grate positioned within said fire box below said aperture to receive materials falling from said drying plate to be burned, said grate being positioned within said fire box at a location that will divide the compartment into an ash pit and a burning chamber, preheating

means projecting through said front wall and located below the drying plate to evaporate the water vapor from the material upon the drying plate by the heat from the preheating means.

2. An incinerator comprising front, rear and side walls defining a chamber, a partition extending across said chamber and dividing same into a fire box and a drying compartment, a chimney formed in the roof of said fire box for carrying off the fumes and also acting as a passage for feeding the material to be burned from a higher level directly into the fire box for burning, the rear wall above said fire box being raked towards the partition wall to form a restricted chimney opening for said fire box, said partition having an aperture therein providing communication between said fire box and said drying chamber, an inclined drying plate mounted between the front and partition walls with one end projecting through the aperture into the fire box at a point intermediate the top and bottom of said aperture and having the other end extending into said drying compartment, a fire grate positioned within said fire box below said aperture to receive materials falling from said drying plate to be burned, said grate dividing the compartment into an ash pit and a burning chamber, preheating means projecting through said front wall and located below the drying plate to evaporate the water vapor from the material upon the drying plate by the heat from the preheating means, means for feeding the material to be burned into the drying chamber, and ducts in the partition above the aperture and establishing communication between said drying chamber and said chimney for carrying off the vapor created by the drying plate and to allow same to pass out through the chimney.

3. An incinerator comprising front, rear and side walls defining a chamber, a partition extending vertically across said chamber and dividing same into a fire box and ash pit, and a drying compartment, a chimney formed in the roof of said fire box for carrying off the fumes and acting as a passage for feeding the material to be burned directly into said fire box from a higher elevation, said partition having an aperture therein providing communication between said fire box and said drying compartment, an inclined drying plate having one end received along the median line of said aperture to form upper and lower openings in said aperture, and said plate extending into said drying compartment between said partition and the front wall of the aforesaid chamber, preheating means projecting through the front wall of said chamber and located below said drying plate to evaporate moisture from the material lying on said plate ducts in said partition above the aperture establishing communication between said drying compartment and said chimney for carrying water vapor from the material on the drying plate and allowing same to pass up through the chimney, means providing access for cleaning the fire box and ash pit, and means to allow feeding of the material to be burned into the drying chamber.

4. An incinerator comprising front, rear and side walls defining a chamber, a partition extending vertically across said chamber and dividing same into a rear fire box and a front drying compartment, a chimney communicating with said fire box at the top thereof, said partition forming a front enclosure for said chimney, said partition also having an opening therein to allow the material to be burned to be fed therethrough into

said fire box, the roof of said fire box being restricted at its rear side where it joins said chimney to control the passage of hot gases from said fire box, a fire grate disposed within said fire box and dividing it into an ash pit and a fire chamber, said partition having an aperture therein establishing communication between said fire box and said drying compartment, an inclined drying plate received along the median line of said aperture to form upper and lower openings, and extending into said drying compartment between said partition and the front wall of the aforesaid chamber, preheating means projecting through said aforementioned front wall and located below the drying plate to evaporate the moisture from the material on said drying plate, ducts in said partition near the roof of the drying compartment and establishing communication between said drying compartment and said chimney for carrying water vapor from the material on the 20 drying plate and allowing same to pass up through

the chimney, means providing access for cleaning the fire box and pit, and means to allow feeding of the material to be burned into the drying chamber.
